United States Patent Office.

PHINEAS JONES, OF NEWARK, NEW JERSEY.

Letters Patent No. 74,373, dated February 11, 1868.

IMPROVEMENT IN REIN-HOLDER.

The Schedule referred to in these Letters Patent and making part of the same.

TO ALL WHOM IT MAY CONCERN:

Be it known that I, PHINEAS JONES, of Newark, in the county of Essex, and State of New Jersey, have invented a new and improved Rein-Holder; and I do hereby declare the following to be a full and exact description thereof, reference being had to the accompanying drawings, which make a part of this specification, and in which—

Figure 1 is a perspective view of my device, representing it in position on the rein.

Figure 2 is a vertical longitudinal section of the same.

Similar letters of reference indicate corresponding parts in both views.

The subject of my invention is a jointed clamp, adapted to automatically and securely grieve the rein, but readily adjustable thereon, and affording a convenient bearing for the hand of the driver, as hereinafter explained.

In the drawings, A A represent a pair of flaps or plates of metal, which may be covered with leather or other material, and are provided with ears B B, projecting endwise and forward from each corner of the straight end of each flap, for the reception of rivets C C, to form a hinge connection. The endwise projection of the ears B forms a throat or cavity between the ends *a a* of the flaps for the reception of the rein D, and the forward projection of the said ears imparts the character of levers to the flaps, so that pressure applied to the front of the device by the hand of the driver, as illustrated in fig. 1, will cause the ends *a a* to grieve the rein D more tightly as more force is applied. By a slight pressure of the thumb upon one flap, the grieve is instantly loosened, so that the clamp may be slipped forward or backward on the rein, as desired. When not in use the clamp may fold down upon the rein, as shown by red lines in fig. 2, so as to be out of the way, but will cling sufficiently to secure it from slipping out of reach.

The ordinary way of holding the reins cramps the hands and prevents the circulation of the blood, whereas with my improvement the reins can be held with the fingers straight, allowing the wearing of heavy gloves, and leaving the circulation free.

Having thus described my invention, what I claim as new, and desire to secure by Letters Patent, is—

The adjustable rein-holder or clamp A B C, adapted to grieve the rein with a lever pressure, when drawn by the hand of the driver, substantially as and for the purposes set forth.

PHINEAS JONES.
